KNITTING MACHINE

Robert H. Lawson, Pawtucket, R. I., assignor to Scott & Williams, Incorporated, Laconia, N. H., a corporation of Massachusetts

Application January 28, 1955, Serial No. 484,649

4 Claims. (Cl. 66—107)

This invention relates to knitting machines and has particular reference to a sinker construction suitable for knitting in which stitches are drawn behind sinker nebs.

In the knitting of ladies' sheer hosiery, in particular, it has been found advantageous in the production of uniform loops to draw stitches behind the nebs of sinkers in contrast with the more usual practice of drawing stitches over sinker ledges in front of or inwardly of the sinker nebs. However, in the adoption of this process of drawing stitches behind the nebs, it has been found that difficulties are encountered particularly in fine gauge machines in that at times, when needles were raised to tuck height, their latches were liable to cross the top of the sinker, or drag on the side thereof, and, being restrained thereby, the latches would then either break the loop of yarn attempting to open the latch or, by robbing yarn from adjacent stitches, produce badly distorted stitches. Whether breakage or only distortion occurred depended, in general, upon how tight or loose the fabric was being knit. This occurred because in machines having thirty-four or more needles per circumferential inch the needles and sinkers are so closely spaced that the latch blade, being necessarily quite thin and flexible, has a tendency to cross the sinker as just mentioned, although in machines having less needles per inch the spacing is generally sufficient to make such crossing unlikely.

In accordance with the present invention, the rear platform of each sinker is shortened to substantially the minimum extent necessary to insure proper drawing of a loop, or said platform may be eliminated entirely, the sinker being cut away to provide clearance for the needle latch even though during the opening movement of the latch the latch may cross the plane of the sinker. Tighter fabric may thus be knit without breakage, and both tight and loose fabrics may be knit without stitch distortion.

The general object of the invention relates to the attainment in the fashion indicated of proper stitch formation particularly in fine gauge machines, and this and other objects of the invention relating particularly to details of construction and operation will become apparent from the following description, read in conjunction with the accompanying drawing, in which:

Figure 1 is a fragmentary sectional view in the region of the upper end of a needle cylinder of a circular machine showing, in particular, the positions assumed by the operating instrumentalities at the time a latch is being opened by the rise of a needle through a previously formed loop; and

Figure 2 is a similar sectional view but showing the drawing of a loop over the sinker ledge behind the neb.

The machine illustrated is of the circular revolving needle cylinder type and in the figures of the drawing the upper portion of the needle cylinder is shown at 2, being provided with needle slots 4 in which there slide conventional latch needles 6 provided with hooks 8 and latches 10, the latter being pivoted at 12. The needles are moved in conventional fashion through the medium of cams operating on their butts, not shown. A conventional sinker

2

dial is indicated at 14 and is surmounted by the conventional sinker cap 16 provided with the usual sinker cams 18 for acting upon but surfaces on sinkers 20 which are mounted to slide between adjacent needles in slots in the sinker dial, the inner portions of the sinkers being guided by the portion 24 of an inside sinker ring 22 entering the slots 26 in the sinkers and also providing slots 27 for the guidance of the inner portions of the sinkers.

Each of the sinkers is provided with a neb 28 which faces inwardly and overlies the forward sinker ledge 30. At the rear of each sinker neb 28 there may be provided a ledge 32 having a radial extent which is substantially only sufficient to underlie and hold the yarn as it is drawn by the needles. To the rear or outside of the ledge 32 the sinker is cut away to provide a clearance space 34 for the free movement of the needle latches 10.

In the operation of the arrangement just described, referring first to Figure 2, the loops are drawn by the needles over the ledge 32 behind the sinker nebs 28, the ledges 32 in this operation being in approximate axial alignment with the interiors of the needle hooks. As will be clear from Figure 2, the ledges 32 must extend radially outwardly only to a relatively slight extent sufficient to insure that the yarn as it is drawn downwardly by the needles does not miss the ledges, the ledges preferably being substantially horizontal so as not to have any outward camming action on the yarn. Following the loop drawing movement, the sinkers are retracted slightly as the needles are raised to tuck height and then, as the needles approach the position where yarn is taken, the sinkers are fully retracted to cause their nebs to ride under the newly drawn loops with resulting positioning of the yarn in the loops to secure uniformity, the drawn loops being then ultimately located on the ledges 30 inwardly of the nebs 28. The actions upon the yarns which are thus accomplished are well known and need not be described in detail.

The invention is particularly concerned with what occurs as the needles rise following the subsequent inward movements of the sinkers. As the needles rise to tuck height, as illustrated in Figure 1, the loops thereon engage the latches, causing the latches to swing to open position with ultimate clearing as the needles continue to rise to clearing height. Heretofore, the ledges 32 have continued horizontally outwardly to positions substantially beyond the rear of the nebs and, under such circumstances, particularly in fine gauge machines, latches have moved laterally to cross and become caught on these ledges. In accordance with the present invention, the sinkers are cut away as at 34 to provide a clearance space so that as the latches open as illustrated in Figure 1, even though they may move laterally, they cannot engage any upper edge portions of the sinkers. It may be noted, considering Figure 1, that the upper edge of the clearance 34 is shown at such position that if the latch 10 swung to full open position about the illustrated position of pivot 12 the spoon of the latch might engage the upper edge of the sinker at the clearing space 34. However, in actual practice, the swinging of the latch 10 to full open position occurs simultaneously with continued upward movement of the pivot point 12, the result being that the spoon of the latch does not swing in a circular arc about the illustrated position of pivot 12 but, rather, in a somewhat oval or elliptical path rising above such hypothetical circular arc. Also, when the latch 10 is in a nearly horizontal position it has a minimum of support from the cheek of the needle with a consequence that it will readily contact any closely bounding piece, whereas when said latch achieves a more fully open position it becomes better supported by the needle cheeks and can be more closely bounded without danger of the tip of the latch striking said boundaries. Accordingly, in actual practice, a clearance such as indicated at 34 may be provided leaving, despite the adequate

clearance, a maximum amount of metal in the main body portion of the sinker to insure proper stiffness of the sinker itself. It may be noted that where the latch 10 actually overlaps, during opening, the ledge 32, this portion of the latch being closely adjacent to the pivot could not, except due to very excessive bending of the latch, engage the sinker. Thus, it is not required that there should be a cut-away portion of the sinker below the ledge 32.

The above discussion of the path of the spoon of the latch may be further made clear by reference to the patent to Moss No. 2,333,667 which illustrates in successive positions of opening a latch the path of the latch spoon.

It will be evident from the foregoing that in accordance with the invention provision is made to prevent arresting by the upper edge of a sinker of a needle latch during its opening movement and, thus, there is prevented breakage of the loops carried on the needle during the needle movements toward clearing height.

What is claimed is:

1. In a fine gauge circular hosiery knitting machine, independently movable latch needles, and independently movable sinkers cooperating with the needles for the formation of stitches, each of said sinkers comprising a neb and a ledge of short radial extent located behind said neb and providing a horizontal platform having a radial extent substantially only sufficient to underlie and hold yarn as loops are drawn by the needles, said sinker being cut away substantially vertically behind said ledge and throughout substantially the region adjacent to the path of the outer portion of a needle latch during opening movement thereof under the action of yarn extending across the needle behind said neb.

2. A sinker adapted for use in a fine gauge circular hosiery knitting machine in association with latch needles, said sinker comprising a neb and a ledge of short radial extent located behind said neb and providing a horizontal platform having a radial extent substantially only sufficient to underlie and hold yarn as loops are drawn by the needles, said sinker being cut away substantially vertically

behind said ledge through substantially the region adjacent to the path of the outer portion of a needle latch during opening movement thereof under the action of yarn extending across the needle behind said neb.

5. In a fine gauge circular hosiery knitting machine, independently movable latch needles, and independently movable sinkers cooperating with the needles for the formation of stitches, each of said sinkers comprising a neb and a ledge of short radial extent located behind said neb and providing a horizontal platform having a radial extent substantially only sufficient to underlie and hold yarn as loops are drawn by the needles, said sinker being cut away substantially vertically behind said ledge from a point substantially in circumferential alignment with the point of an adjacent needle hook as the needle rises throughout substantially the region adjacent to the path of the outer portion of a needle latch during opening movement thereof under the action of yarn extending across the needle behind said neb.

10. 3. In a fine gauge circular hosiery knitting machine, independently movable latch needles, and independently movable sinkers cooperating with the needles for the formation of stitches, each of said sinkers comprising a neb and a ledge of short radial extent located behind said neb and providing a horizontal platform having a radial extent substantially only sufficient to underlie and hold yarn as loops are drawn by the needles, said sinker being cut away substantially vertically behind said ledge from a point substantially in circumferential alignment with the point of an adjacent needle hook as the needle rises throughout substantially the region adjacent to the path of the outer portion of a needle latch during opening movement thereof under the action of yarn extending across the needle behind said neb.

15. 4. A sinker adapted for use in a fine gauge circular hosiery knitting machine in association with latch needles, said sinker comprising a neb and a ledge of short radial extent located behind said neb and providing a horizontal platform having a radial extent substantially only sufficient to underlie and hold yarn as loops are drawn by the needles, said sinker being cut away substantially vertically behind said ledge from a point substantially in circumferential alignment with the point of an adjacent needle hook as the needle rises throughout substantially the region adjacent to the path of the outer portion of a needle latch during opening movement thereof under the action of yarn extending across the needle behind said neb.
